Primary Examiner — Catherine A Tuttle

(74) Attorney, Agent, or Firm — Luedeka Neely Group,
PC(57) **CLAIM**

The ornamental design for a handheld game, as shown and described.

DESCRIPTION

FIG. 1 is a perspective view of a handheld game showing my new design.

FIG. 2 is a top view thereof.

FIG. 3 is a bottom view thereof.

FIG. 4 is an enlarged scale front end view thereof.

FIG. 5 is an enlarged scale rear end view thereof.

FIG. 6 is a right side view thereof; and,

FIG. 7 is a left side view thereof.

The broken lines in the drawings are included for the purpose of illustrating elements of the handheld game that form no part of the claimed design.

1 Claim, 3 Drawing Sheets(56)
